RACK FOR PATIENT UTENSILS OR THE LIKE

Alfred E. Arnett, 7600 N. Broadway,
Wichita, Kans. 67219

Filed Jan. 2, 1976, Ser. No. 646,265

Term of patent 14 years

Int. Cl. D6—04

U.S. Cl. D6—134

FIG. 1

FIG. 1 is a perspective view of a rack for patient utensils or the like incorporating my new design;

FIG. 2 is a front elevational view; and

FIG. 3 is a top plan view.

I claim:

The ornamental design for a rack for patient utensils or the like, as shown.
